UNITED STATES PATENT OFFICE.

OTTO H. SCHRAEGER, OF KALAMAZOO, MICHIGAN.

TEMPORARY BINDER.

No. 918,707.

Specification of Letters Patent. Patented April 20, 1909.

Application filed September 3, 1907. Serial No. 391,085.

To all whom it may concern:

Be it known that I, OTTO H. SCHRAEGER, a citizen of the United States, residing at Kalamazoo, Kalamazoo county, Michigan, have invented certain new and useful Improvements in Temporary Binders, of which the following is a specification.

This invention relates to improvements in temporary binders or loose sheet holders.

10 The main objects of this invention are, first, to provide an improved temporary binder or loose sheet holder in which the binding mechanism is formed of sheet metal; second, to provide an improved temporary binder for loose sheet holders in which the binding mechanism is formed of sheet metal, which may be of comparatively light weight, and at the same time one which is very strong and durable; third, to provide an improved temporary binder or loose sheet holder which is very quickly and easily adjusted; and fourth, to provide an improved temporary binder or loose sheet holder which is very economical to produce.

25 Further objects, and objects relating to structural details, will definitely appear from the detailed description to follow.

I accomplish the objects of my invention by the devices and means described in the 30 following specification.

The invention is clearly defined and pointed out in the claims.

A structure embodying the features of my invention is clearly illustrated in the 35 accompanying drawing, forming a part of this specification, in which,

Figure 1 is a detail inside view of a structure embodying the features of my invention with the covers extended or open, portions 40 being broken away to show the arrangement of the parts; Fig. 2 is a detail longitudinal section taken on a line corresponding to line 2-2 of Fig. 1; Fig. 3 is a detail transverse section taken on a line corresponding to line 45 3-3 of Fig. 2; Fig. 4 is an end elevation of the binding or back portion; Fig. 5 is an enlarged detail section thereof taken on a line corresponding to line 5-5 of Fig. 4; Fig. 6 is a detail inside view of a modified structure; Fig. 7 is a detail end elevation of the structure appearing in Fig. 6; Fig. 8 is a longitudinal section, taken on a line corresponding to line 8-8 of Fig. 6; Fig. 9 is an enlarged detail longitudinal section taken on 50 a line corresponding to the broken line 9-9 of Fig. 6; and Fig. 10 is an enlarged detail

taken on a line corresponding to line 10-10 of Fig. 7.

In the drawing, the sectional views are taken looking in the direction of the little 60 arrows at the ends of the section lines, and similar numerals of reference refer to similar parts throughout the several views.

Referring to the drawing, the back pieces 1 are formed of sheet metal and are provided with forwardly-projecting flange-like 65 end portions 2. These backs and ends are adapted to telescope upon each other. The ends of one of the back pieces are provided with longitudinal slots 3 adapted to receive 70 the screws 4 carried by the ends of the other back piece; see Figs. 4 and 5. The screws 4 are provided with suitable nuts 5 which may be turned up to secure the parts adjustably 75 together.

The posts 6 are formed integrally with the back pieces by folding the back pieces upon themselves, as clearly appears from Fig. 3. I preferably provide T-shaped posts illustrated, although it will be obvious that 80 any shaped posts desired can be secured by this means. The posts of one back piece are arranged to telescope within the posts of the other, thus forming adjustable binding posts 85 for the sheets or leaves to be secured by the binder.

The back pieces 1 are provided with flange-like clamping members 7, which are also formed integrally therewith. The ends of the clamping members are preferably 90 turned down over the end pieces 2 and secured thereon by soldering or brazing, thereby effectively supporting the end pieces as well as supporting the clamping members. The clamping members are also preferably 95 soldered or brazed to the outer ends of the binding posts, which makes the structure very strong and rigid, although made of comparatively light material, the one part serving as a brace or support for the other. 100

The clamping members are preferably provided with bead-like hinge members or ears 9 on their inner edges adapted to receive the hinge pivots 10 for securing the covers. These hinge pivots are preferably 105 formed of wire and are provided with arms 11 to which the covers 12 are secured. The covers are preferably made up of layers, as illustrated, so that the arms 11 may be clamped or secured between the same; see 110 Figs. 1 and 2. By this simple means, I thus effectively secure the covers, and at the

same time the cover connection is a very economical one.

In the modified construction shown in Figs. 6 and 10, the post members 6 are formed on the ends of the backs instead of intermediate the ends, as in the construction shown in Figs. 1 to 5, inclusive, and a positive adjusting means is provided for the clamping members; that is, the end portions 10 2 are turned inwardly to form extensions 13, which are provided with forwardly-projecting flanges 14, the posts being carried by the ends of these flanges. This arrangement provides a chamber at the rear of the posts for 15 the adjusting mechanism, which preferably consists of the screw 23 journaled in bearings 15 and 16 at each end of the screw. This screw is reversely threaded and is provided with a pair of nuts 17, which are 20 provided with perforated ears to receive the links 18. These links are crossed and connected by the ears 19 to the back members. By manipulating the screw by the aid of the key 20 the nuts are moved toward or from 25 each other, thus drawing the back members together or forcing them apart, thereby adjusting the binder. In this construction the sheet metal backs are preferably covered with leather or other suitable covering, as 30 22. The covers 12 are secured to the back members by means of the hinge plates 21, which are hinged at the forward edges of the clamping members in substantially the same manner as the hinge members 11 in the 35 structure illustrated in Fig. 1.

I show in the accompanying drawing two forms of my invention, or two structures embodying the same. I desire to state, however, that it could be modified in various 40 ways without departing from my invention.

Having thus described my invention, what I claim as new and desire to secure by Letters Patent is:

1. In a temporary binder, the combination 45 of a pair of telescoping back pieces formed of sheet metal; forwardly-projecting flange-like end pieces for said back pieces formed integrally therewith, the end pieces of one of said back pieces being longitudinally slotted; screws carried by the end pieces of 50 the other back pieces adapted to engage said slotted end piece; thumb nuts for said screws whereby said back pieces are adjustably secured together; binding posts arranged 55 transversely of said back pieces and formed integrally therewith by folding the said back pieces upon themselves, the binding posts of one of said back pieces being adapted to telescope with those of the other; 60 clamping members formed integrally with said back pieces, the ends of said clamping members being folded over the said end pieces of said back pieces and secured thereto and to the outer ends of said binding posts; 65 bead-like hinge members formed on the for-

ward edges of said clamping members; pivot members formed of wire engaged by said hinge members, said pivot members having projecting arms at the ends thereof; and covers secured to the said arms of said 70 pivot members.

2. In a temporary binder, the combination of a pair of telescoping back pieces formed of sheet metal; forwardly-projecting flange-like end pieces for said back pieces formed 75 integrally therewith, the end pieces of one of said back pieces being longitudinally slotted; screws carried by the end pieces of the other back piece adapted to engage said slotted end piece; thumb nuts for said screws 80 whereby said back pieces are adjustably secured together; binding posts arranged transversely of said back pieces and formed integrally therewith by folding the said back pieces upon themselves, the binding 85 posts of one of said back pieces being adapted to telescope with those of the other; and clamping members formed integrally with said back pieces, the ends of said clamping members being folded over the said end 90 pieces of said back pieces and secured thereto and to the outer ends of said binding posts.

3. In a temporary binder, the combination of a pair of telescoping back pieces formed of sheet metal; forwardly-projecting flange-like end pieces for said back pieces formed 95 integrally therewith; binding posts arranged transversely of said back pieces and formed integrally therewith by folding the said back pieces upon themselves, the binding posts of one of said back pieces being adapted to telescope with those of the other; clamping members formed integrally with said back pieces, the ends of said clamping members being folded over the said end 100 pieces of said back pieces and secured thereto and to the outer ends of said binding posts; bead-like hinge members formed on the forward edges of said clamping members; pivot members formed of wire engaged by said hinge members, said pivot members having projecting arms at the ends thereof; and covers secured to the said arms 105 of said pivot members.

4. In a temporary binder, the combination 115 of a pair of telescoping back pieces formed of sheet metal; forwardly-projecting flange-like end pieces for said back pieces formed integrally therewith; binding posts arranged 120 transversely of said back pieces and formed integrally therewith by folding the said back pieces upon themselves, the binding posts of one of said back pieces being adapted to telescope with those of the other; and clamping members formed integrally with 125 said back pieces, the ends of said clamping members being folded over the said end pieces of said back pieces and secured thereto and to the outer ends of said binding posts.

5. In a temporary binder, the combination of a pair of telescoping back pieces formed of sheet metal; binding posts arranged transversely of said back pieces and formed integrally therewith by folding the said back pieces upon themselves, the binding posts of one of said back pieces being adapted to telescope with those of the other; clamping members formed integrally with said back pieces, said clamping members being secured to the outer ends of said binding posts; bead-like hinge members formed on the forward edges of said clamping members; pivot members formed of wire engaged by said hinge members, said pivot members having projecting arms at the ends thereof; and covers secured to the said arms of said pivot members. 40
- 10 6. In a temporary binder, the combination of a pair of telescoping back pieces formed of sheet metal; binding posts arranged transversely of said back pieces and formed integrally therewith, the binding posts of one of said back pieces being adapted to telescope with those of the other back pieces having inwardly projecting flange-like end pieces formed integrally therewith; and clamping members formed integrally with said back pieces folded over and secured to the ends of the said end pieces whereby the parts brace and support each other. 50
- 15 7. In a temporary binder, the combination with the clamping members formed of sheet metal and having bead-like hinge members formed on their forward edges by rolling the metal upon itself; pivot members formed of wire engaged by said hinge members, said pivot members having projecting arms thereon; and covers made up of layers of material secured upon said arms by embedding the arms therein. 55
- 20 8. In a temporary binder, the combination of a pair of telescoping back pieces formed of sheet metal; binding posts arranged transversely of said back pieces and formed integrally therewith by folding the metal upon itself, the binding posts of one of said back pieces being adapted to telescope with those of the other; and clamping members formed integrally with said back pieces, said clamping members being folded upon and secured to said binding posts whereby the parts 60
- 25 9. In a temporary binder, the combination with the clamping members formed of sheet metal and having bead-like hinge members formed on their forward edges by rolling the metal upon itself; pivot members formed of wire engaged by said hinge members, said pivot members having projecting arms thereon; and covers made up of layers of material secured upon said arms by embedding the arms therein. 70
- 30 35

In witness whereof, I have hereunto set my hand and seal in the presence of two witnesses.
